UNITED STATES PATENT OFFICE

RAYMOND L. BARKER, OF CHICAGO, ILLINOIS

DESIGN FOR A BODY TREATING DEVICE

Application filed June 4, 1930. Serial No. 35,897. Term of patent 14 years.

all whom it may concern:

Be it known that I, RAYMOND L. BARKER, a citizen of the United States, residing at Chicago, in the county of Cook and State of Illinois, have invented a new, original, and ornamental Design for a Body Treating Device, of which the following is a specification, reference being had to the accompanying drawings, forming part thereof.

In the drawings,—

Fig. 1 is a plan view;

Fig. 2 is a side elevational view; and

Fig. 3 is an end elevational view of a body treating device embodying my new design.

The smooth curved surfaces of the body of the device blend together, are bright and highly polished and present mirror-like reflecting surfaces all in sharp contrast to the dull appearing handle attached thereto which has a plurality of sharply defined, long, narrow and flat panel-like surfaces.

I claim:—

The ornamental design for a body treating device substantially as shown and described

RAYMOND L. BARKER.
